UNITED STATES PATENT OFFICE.

JOHN H. FOX, OF PITTSBURGH, PENNSYLVANIA, ASSIGNOR TO PITTSBURGH PLATE
GLASS COMPANY, A CORPORATION OF PENNSYLVANIA.

APPARATUS FOR MAKING SHEET GLASS.

Application filed March 18, 1926. Serial No. 95,590.

The invention relates to an apparatus for making sheet glass in ribbon form by a combined pouring and rolling operation. The molten glass may be supplied to the rolling apparatus by ladling it from a melting tank, but it is preferably supplied from glass melting pots as in the regular plate casting operation, the batch being melted, and the glass fined, in individual pots in a pot furnace, from which they are removed by means of a crane and carried to the rolling apparatus, where they are poured onto the surface of a roll of large diameter. The glass is rolled out to proper thickness by a driven sizing roll mounted in opposition to the large roll, which latter is caused to revolve carrying the glass between the two rolls. The invention has for its principal objects; the provision of an improved arrangement of the rolls; and the provision of improved means for positively maintaining the opposing surfaces of the rolls at a constant distance apart as the rolling progresses, so as to produce a sheet of uniform thickness throughout its length regardless of any deformation or warping of the large roll from truly cylindrical shape, such as usually occurs in the course of time, and incident to the wide variation in temperature in different segments of the roll under the action of the molten glass. Certain embodiments of the invention are illustrated in the accompanying drawings, wherein:

Figure 1 is a section on the line I—I of Fig. 5. Fig. 2 is a plan view on a reduced scale. Fig. 3 is a section on the line III—III of Fig. 1. Fig. 4 is a section on the line IV—IV of Fig. 1. Fig. 5 is a plan view. And Fig. 6 is a section through a modified construction.

Referring to the drawings, 1 is the casting roll mounted for rotation on the axle 2, and 3 is a sizing roll for producing the desired thickness in the sheet 4, which passes through the roller leer 5 and is annealed. The roll 1 comprises a shell portion bolted to the spider 6 and preferably seated in a pit 7 containing a body of water for cooling the roll. This cooling may be also accomplished by means of the perforated pipes 8 through which a flow of air is supplied. Preliminary to the starting of the operation, it is desirable to heat the roll and this is accomplished from the perforated gas pipes 9 with a shield 10 lying to the rear thereof. The body of glass

for forming the sheet is poured into the pocket between the rolls 1 and 3, being held in at the sides by means of the triangular side plates 11 resting upon the periphery of the roll 1 and provided at their rear ends 60 with the transverse shaft 12^a carrying the rollers 12 for supporting such ends and holding them against separation. The plates 11 are preferably provided with a plurality of inwardly projecting spikes 13 (Figs. 1 and 65 5) which serve to hold back the body of glass at its side portions and prevent a too rapid movement between the rolls. When the pocket of glass is exhausted, the glass in contact with the spikes and side plates pulls 70 away so that little or no cleaning of these members is required.

Power for rotating the rolls 1 and 3 is supplied from the motor 14, such motor operating to drive the tumbler shafts 15 and 16 75 through the intermediary of a clutch 17, and reducing and speed changing gearing in the casings 18 and 19. The tumbler shaft 15 is connected to a drive shaft 20 carrying the gear 21, and this gear 21 meshes with a large 80 drive gear 22 bolted to the edge of the roll 1 at its periphery. The other tumbler shaft 16 is connected at its end to the shaft 23 which carries the sizing roll 3. This shaft is hollow and is water cooled by means of 85 the connections 24, 24 communicating with swivels 25, 25 on the roll shaft. The ends of the roll are carried in the bearings 26, 26 having the caps 27, 27 and being slidably mounted in the housing 28, such housing 90 being rigidly supported with respect to the mounting of the casting roll 1. The bearing members 26, 26 are pressed yieldingly downward by means of the springs 29, 29, whose tension may be adjusted from the 95 screws 30, 30 extending through the brackets 31, 31 bolted to the housing.

In order to definitely space the sizing roll 3 with respect to the periphery of the casting roll 1, and thus maintain the thickness 100 of the sheet uniform, regardless of any warping of the roll 1, the rolls 32, 32 are preferably employed, such rolls being carried in brackets 33, 33 and bearing against the periphery of the casting roll, as indicated in Figs. 3 and 4. The brackets 33 are of L-form, as indicated in Fig. 1 and have upright legs 34 slidably mounted in the bearing members 26. These brackets 33 are adjusted by means of screws 35 (Fig. 3) 110

threaded through nuts secured in the upper ends of the legs 34 and having thrust bearings 36 held against upward movement by the end wall 37 of the bearing member 26, 5 as indicated in Fig. 3. The screws are provided with worm wheels 38, and these worm wheels are engaged by worms carried upon the transverse shaft 39, such shaft having an operating handle 40 at its end. By adjusting the brackets 33 up and down, the space between the casting and sizing rolls may be adjusted to produce glass of any desired thickness, a downward movement of the brackets and their rolls serving to increase the space between the sizing and casting rolls, while a movement upward serves to decrease such space. In case the casting roll 1 becomes warped or bulged, the spacing means take care of this condition and 20 still maintain the peripheries of the sizing and casting rolls at a uniform distance apart throughout the rotation of the casting roll, thus producing a glass sheet or ribbon which is of uniform thickness. In operating the apparatus, the pocket between the side plates 11, 11 is supplied with glass from a pot, the entire contents of the pot being preferably supplied to the pocket before the rolling operation is started. The casting and sizing rolls are then started and the ribbon or sheet of glass 4 is rolled out into the leer 5 until the contents of the pocket is exhausted, the glass as it leaves the rolls first passing over the water cooled platen 41 and then 30 over the cooled rolls 42 in the leer. The sheet or ribbon is allowed to harden in the leer and becomes annealed in a gradually decreasing temperature as it passes therethrough, being cut up into sections of suitable length as it emerges from the end of the leer.

Fig. 6 shows a modified spacing means for fixing the distance between the casting roll 1 and sizing roll 3. This spacing means 45 comprises the angle members 43, preferably made in sections, and bolted to the sizing rolls, as indicated. The thickness of the flanges on the members 43, 43 lying between the peripheries of the two rolls determines 50 the thickness of the glass sheet produced. Different thicknesses of glass are taken care of by removing the members 43 and substituting others having flanges of different thicknesses. This arrangement may be modified by placing the spacing members 43, 43 upon the casting roll instead of upon the sizing roll, but this arrangement is not so desirable because of the greater size of

the spacing members incident to the large diameter of the casting roll. The advantage of my construction will be readily apparent to those skilled in the art, the liability of a roll of large size to warp and bulge being well known, and the arrangement to which the present invention is particularly directed serving to overcome this difficulty and make it possible to cast a sheet of uniform thickness, even though the casting roll departs appreciably in the course of time from its original accurate contour. 70

What I claim is:

1. In apparatus for making sheet glass, a casting roll of large diameter mounted for rotation, a driven sizing roll above the casting roll positioned so as to provide a pocket 75 between the two rolls for receiving the molten glass to be rolled, bearings in which the sizing roll is journaled mounted for movement toward the casting roll, spacing means mounted to move with said bearings 80 in fixed relation thereto and contacting with the periphery of the casting roll, and a runway for receiving the glass sheet formed between the rolls.

2. In apparatus for making sheet glass, 85 a casting roll of large diameter mounted for rotation, a driven sizing roll above the casting roll positioned so as to provide a pocket between the two rolls for receiving the molten glass to be rolled, bearings in which the 90 sizing roll is journaled mounted for movement toward the casting roll, spacing means mounted to move with said bearings in fixed relation thereto and contacting with the periphery of the casting roll, means for adjusting the position of said spacing means 95 with respect to the bearings, and a runway for receiving the glass sheet formed between the rolls.

3. In apparatus for making sheet glass, 100 a casting roll of large diameter mounted for rotation, a driven sizing roll above the casting roll positioned so as to provide a pocket between the two rolls for receiving the molten glass to be rolled, bearings in which the 105 sizing roll is journaled mounted for movement toward the casting roll, a spacing roll adjacent each bearing mounted to move therewith and contacting with the periphery of the casting roll adjacent its edges, and 110 a runway for receiving the glass sheet formed between the rolls.

In testimony whereof, I have hereunto subscribed my name this 12th day of March, 1926.

JOHN H. FOX.
